UNITED STATES PATENT OFFICE.

WILLIAM ARTHUR DARLING, OF KANSAS CITY, MISSOURI.

CUTTING-BLADE ATTACHMENT.

1,359,339.

Specification of Letters Patent. Patented Nov. 16, 1920.

Application filed November 1, 1919. Serial No. 335,007.

To all whom it may concern:

Be it known that I, WILLIAM A. DARLING, a citizen of the United States, residing at Kansas City, in the county of Jackson and 5 State of Missouri, have invented new and useful Improvements in Cutting-Blade Attachments, of which the following is a specification.

The object of the invention is to provide 10 a simple and inexpensive cutting blade attachment for hammers such as are used by carpenters and similar mechanics, the blade being effectively attachable without supplemental fastening means so that it may be 15 used at a moment's notice when required and yet when not needed will not obstruct the ordinary use of the hammer or interfere with the operation thereof in the performance of its ordinary functions; and with 20 these objects in view the invention consists in a construction and combination of parts of which a preferred embodiment is shown in the drawing, it being understood that changes in form and proportion may be 25 sorted to within the scope of the claim without departing from the principles involved.

In the drawing:

Figure 1 is a side view of the blade attachment embodying the invention applied 30 in the operative position to a hammer head.

Fig. 2 is a similar view of the attachment disconnected from the hammer head.

Fig. 3 is an edge view to show the hammer head seat and the lug for engaging the 35 claw of the hammer.

Fig. 4 is a detail sectional view on the plane indicated by the line 4—4 of Fig. 1.

The attachment consisting essentially of the blade 10 is adapted for attachment to an 40 ordinary hammer head shown at 11 and provided with the usual claw 12 which is bifurcated to form a nail extractor. Said blade is provided with a segmental seat 13 adapted

to fit and receive the exterior convexed surface of the claw of the hammer head bearing 45 uniformly thereon from the extremity of the claw to a point preferably beyond the line of the eye, and adjacent to the base of the hole 15, so that said seat has a bearing both longitudinally and transversely with reference to the hammer head. Located in the seat at one end opposite the blade is a lug 16 which is undercut at its sides as shown at 17 to receive the inner edges of the members 18 of the claw at opposite sides of the 50 tapered slot or opening formed therein. Said lug is also tapered longitudinally so as to substantially occupy the entire length of the opening representing the bifurcation of the claw. Therefore in use, or when the cutting blade is being employed as an attachment to the hammer head, the possibility of displacement is reduced to the minimum, and the weight and strength of the hammer head are disposed in a column corresponding 55 with the length of the cutting blade to render the latter substantially as efficient as a hatchet blade wherein an integral connection is made between the blade portion and the head of the implement. Obviously the attachment can be dismounted simply by sliding the same in the direction of the curvature of its seat to remove the lug from the bifurcation of the claw. 60

What is claimed is:

An attachment for hammer heads, comprising a body formed as a blade provided at one end with an arcuate widened portion adapted for conforming engagement with the curved outer side of the hammer claw, 80 and formed with a lug T-shaped in cross section for retaining engagement within the bifurcation of the claw.

In testimony whereof I affix my signature.

WILLIAM ARTHUR DARLING.
